CLAIM

The ornamental design for a water tap, as shown and described.

DESCRIPTION

FIG. 1 is a front perspective view of a water tap, showing my new design;

FIG. 2 is a rear perspective view thereof;

FIG. 3 is a front elevation view thereof;

FIG. 4 is a rear elevation view thereof;

FIG. 5 is a left side elevation view thereof, the right side elevation view being a mirror image of FIG. 5;

FIG. 6 is a top plan view thereof;

FIG. 7 is a bottom plan view thereof; and,

FIG. 8 is an enlarged detail view of the portion 8 shown in FIG. 1.

The broken lines in the figures are for the purposes of illustrating portions of the water tap, which form no part of the claimed design. The dot dash broken lines shown in FIGS. 1 and 8 indicate cutoff boundaries for enlarged detail portion views and form no part of the claim.
